UNITED STATES PATENT OFFICE.

SYDNEY I. PRESCOTT, OF NEW YORK, N. Y., ASSIGNOR TO THE AMERICAN TOBACCO COMPANY, OF NEW YORK, N. Y., A CORPORATION OF NEW JERSEY.

MOUTHPIECE-FORMING MECHANISM.

1,105,832.

Specification of Letters Patent.

Patented Aug. 4, 1914.

Application filed May 14, 1906. Serial No. 316,686.

To all whom it may concern:

Be it known that I, SYDNEY I. PRESCOTT, a citizen of the United States, residing at New York, county of Kings, and State of New York, have invented certain new and useful Improvements in Mouthpiece-Forming Mechanism, fully described and represented in the following specification and the accompanying drawings, forming a part of 10 the same.

This invention relates to certain improvements in mechanism for forming cigarette tubes containing mouthpieces, such tubes being used in the manufacture of cigarettes.

15 In machines ordinarily used in which mouthpieces have been made and introduced into cigarette tubes, mouthpiece blanks have been cut from a continuous strip of material by two knives, one of which produced a 20 forming cut extending diagonally across the strip and the other of which severed the mouthpiece blank. In these machines the successive mouthpiece blanks had their narrow ends, produced by the forming cut referred to, extending in opposite directions so 25 that it was necessary, in order to present the blanks properly to the coiling mechanism, to reverse the position of every other mouthpiece blank. The construction of these machines, therefore, necessarily involved a 30 somewhat complicated blank reversing mechanism, and the mouthpiece blanks formed thereby were further objectionable because the diagonal forming cut which extended entirely across the strip produced a blank having a very narrow end which was so weak 35 that when the mouthpiece was coiled up it did not act satisfactorily as a tobacco stop; it being understood, of course, that the tobacco is stuffed into the tubes after the 40 mouthpieces have been inserted therein and into that end of the tubes which is opposite to the end containing the mouthpiece.

45 It is one of the objects of this invention to produce an improved mechanism for forming mouthpiece blanks in which the forming cuts shall be made in such a way as to produce blanks having narrowed necks which shall be sufficiently rigid, after the mouthpiece is completed, to form a tobacco stop.

50 A further object of the invention is to produce an improved mechanism for forming mouthpiece blanks in which the forming cuts shall be made in such a way as to narrow the neck of the mouthpiece on both

sides thereof, the neck of the blank thus formed being sufficiently rigid, after the mouthpiece is completed, to act as a tobacco stop on one edge, the other edge being cut away to improve the appearance of the 60 mouthpiece.

With these and other objects not specifically referred to in view, the invention consists in certain constructions, and in certain parts, improvements and combinations as 65 will be hereinafter fully described and then specifically pointed out.

Referring to the accompanying drawings—Figure 1 illustrates, in plan view, the blank cutting mechanism and a mechanism 70 for forming and inserting mouthpieces, certain parts being shown in section. Fig. 2 is a side elevation of the construction illustrated in Fig. 1, certain parts being shown in section. Figs. 3, 4 and 5 are diagrams 75 illustrating the action of the blank forming devices. Fig. 6 is a plan view of the mechanism for inserting the mouthpiece into the tube and the rerolling mechanism. Fig. 7 is a front elevation of the construction shown 80 in Fig. 6. Figs. 8 and 9 are diagrammatic views illustrating the operation of the winding spindle.

The mouth-piece blanks are, in the particular machine shown, formed from a continuous strip of mouthpiece material indicated at 1 in Figs. 3 and 4, this material being obtained from any suitable source, as a reel, not shown. The strip may be guided in any suitable manner to the devices to be 85 hereinafter described for forming the blanks and the mouthpieces. In the construction illustrated, the strip is laid over a curved guide 2 (see Figs. 1 and 2), this guide being provided, if desired, with a suitable tension spring, as 3, and having its edges raised, as indicated at 4, to form a channel for the strip.

The strip is caused to receive suitable cuts by which the blank is formed and severed from the strip. These cuts may be effected in various ways and by mechanism which differ widely in character. The mechanism will, however, be such as to produce a mouthpiece blank A (see Fig. 5) having a narrow 100 "neck." By this term is meant that part of the blank which is presented to and seized by the coiling devices which form the blank into a mouth piece. While a single cut might, under certain circumstances, be em- 105

ployed for narrowing the end of the mouth-piece blank, in the best constructions and as illustrated, the strip will be given two cuts which extend inward from the edge of the 5 strip and a further cut which intersects these cuts. In the particular construction illustrated, the strip is given two diagonal cuts, indicated at 5, 6, these cuts being produced by knives 7 and 8. These knives 7, 8 10 are, in the particular machine shown, carried by a crosshead 9 mounted on a pair of vertical rods 10 which reciprocate through guides formed in bosses 11, these bosses being formed on a slide 12. This slide 12 is adjustably mounted on an arm 13 secured to the frame of the machine in any suitable manner, the adjustment of the slide being determined by set screws 14, or in any other suitable manner. The upper end of the slide 20 is formed to produce a table which carries a shear block 16, this table also supporting the guide 2 before referred to. In the best constructions and as shown, the knives 7, 8 will be straight knives, thus producing diagonal 25 straight line cuts extending from the edge of the mouth piece strip inward and terminating at points between the edges of the strip. The shear block will, of course, be formed with sides which correspond with the 30 shape of the knives whatever the shape may be.

In the operation of the mechanism, the 35 paper strip is laid under a guide and holder plate 17 which extends forward between the knives, the purpose of this plate being to prevent the strip from being lifted by the return movement of the knives after cutting. The knives may be operated by any 40 suitable mechanism, the character of which will depend on the character of the knives employed. When reciprocating knives of the character illustrated are employed, their movement may be effected through an arm 18 which is secured to a cross head 19 which 45 ties the lower ends of the rods 10 together, this arm being mounted on a rock shaft 20. This rock shaft has connected thereto an operating arm 21 which engages a stud 22 on a block 23 clamped, by means of a screw 24, or 50 in any other suitable manner, to a reciprocating operating rod 25. This rod carries a cam roller 26 which engages the groove of a cam 27 mounted on a shaft 28 suitably journaled in the frame of the machine.

55 In making up rolls of mouthpiece paper, it frequently happens that the paper is broken and the ends are overlapped and pasted together. If such an overlapped portion is allowed to run into the mouthpiece 60 coiling mechanism, the operation of the machine is liable to be interfered with. The best constructions of machines embodying the invention will, therefore, be provided with what may be termed an overlap detector. While the construction of this de-

tector may be varied, in the construction illustrated, it consists of two plates 29, 30 which are spaced at the middle portions a suitable distance to permit a single thickness of mouthpiece paper to pass therethrough, 70 but prevent the passage of more than a single thickness.

Suitable strip forwarding devices will be employed which may be varied widely in construction and location. As shown, these 75 strip forwarding devices comprise a lower roughened roll 31 and an upper roughened roll 32. These rolls, when rolls are employed, may be operated in any desired manner. In the construction illustrated, the 80 rolls will be given an intermittent movement, the roll 31 being mounted on a shaft 33 which has secured thereto a ratchet disk 34. This ratchet disk is operated by means of a spring controlled pawl 35 mounted on a 85 pawl carrier 36, this pawl carrier being hung on a hub 37 which surrounds the shaft 33. The shaft 33 is also provided with a gear 38 on a shaft 39 which shaft carries the roll 32. 90

Whatever be the construction of strip feeding devices employed, they will, in the best constructions, be of such a character that the amount of feed of the strip may be varied so as to vary the size of the mouth-pieces. In the construction illustrated, this 95 is effected by operating the pawl carrier 36 by a connecting rod 40 which is operated from a crank pin 41 mounted on a T-piece 42. This T-piece is secured in a groove in a 100 crank head 43 which is mounted on a shaft 44, the position of the T-piece, and therefore of the crank, being determined by set screws 45. By varying the position of the T-piece the position of the crank 41, and, consequently, the movement of the pawl carrier, can be adjusted, so as to give the rolls a greater or less amount of feeding movement. 105

Whenever the strip feeding devices are 110 adjusted, a corresponding variation can be made in the position of the knives to cause them to make the neck forming cuts in the proper place in the strip, this depending, of course, on the length which the blank is to have when finished. This may be done by 115 shifting the slide 12 on the arm 13, which may be accomplished by loosening the set screws 14. By loosening the screw 24 the clamp block 23 may be correspondingly shifted along the operating rod 25. 120

The devices so far described form the paper strip by cutting the slits 5, 6 before referred to. The strip is then presented to a blank severing knife which may be of any suitable construction. In the construction 125 illustrated, this blank severing knife consists of a pair of shear blades 46, 47, the blade 47 being a stationary blade which rests in a recess 48 in the frame. Passing loosely through this stationary blade 47 is a piv- 130

oted rod 49 on which the movable blade 46 is mounted. This rod is provided with the usual tension or pressure spring 50 by which the blades are held together, this rod being supported in one of the side frames of the machine. The movable shear blade may be operated by any suitable mechanism. In the construction illustrated, there is provided an operating slide 51 which has a recess in its top, indicated by the dotted lines in Fig. 1, in which the end of the blade 46 is received. This slide moves in ways 52 secured to the frame and is provided with a roll 53 (see dotted lines in Fig. 2) which engages in a closed groove on the inner side of a disk 54 mounted on the shaft 44 before referred to.

In the particular construction illustrated, the knife is long enough to produce a blank severing cut which extends from side to side of the strip, this cut being indicated at 55, in Fig. 4. This cut intersects the cuts 5, 6 before referred to and completes the formation of the preceding blank, as appears in Fig. 5. It will be noted that the intersecting cuts sever waste pieces from the blank, these waste pieces being indicated by the dotted lines in Fig. 4.

The severed blank is now ready to be formed up into a mouthpiece which operation may be effected by any suitable mechanism. A slotted coiling spindle is usually employed in machines of this character for converting blanks into mouthpieces, and such a spindle is employed in the particular machine illustrated, and is marked 56 (see Figs. 6, 7, 9). This spindle may be mounted and operated in any desired manner. In the construction illustrated, it is secured by a clamping block 57 to a shaft 58, this shaft being supported in a long bearing 59 mounted in one of the side frames. This shaft 58 carries a pinion 60 which is in mesh with a gear 61 loosely mounted on a tie-rod 62 which extends across the machine. The gear 61 has secured to it a mutilated gear 63 which is driven by segment gear teeth 64 cut in the circumference of the disk 54 before referred to. The gear 63 is provided with a locking segment 65 (see Fig. 2) which co-operates with the untoothed portion of the circumference of the disk 54, such constructions being well-known. It will be understood that the slotted spindle is so located with respect to the cutting off knife that the narrowed forward end of the blank is inserted into the slot in the spindle before the blank severing knife operates, the gearing for operating the spindle being so timed as to be brought into operation immediately after the blank is severed.

It may be here remarked that the formation of the blank in the particular manner illustrated and heretofore described has several distinct advantages. The narrowing

of the end thereof permits the employment of a comparatively short slot in the spindle, thereby making the spindle stiffer. Further, the cutting away of the waste piece formed by the edge of the strip, the cut 5 and the cut 55 makes a short tobacco pocket in the end of the mouthpiece so that when the tobacco filler is inserted in the tube it extends for a short distance into this pocket, thus producing a cigarette which is not liable to break. A cigarette in which the tobacco filler is flush with the inner end of the mouth piece is weak and is liable to bend or break at this point. Further, the removal of the waste piece formed by the edge of the strip, the cut 6 and the cut 55 improves the appearance of the cigarette, for the reason that the end of the blank which is necessarily deformed by the operation of the winding spindle does not show at the outer end of the mouthpiece. In addition to these advantages, the narrowed end of the mouthpiece blank lends itself readily to the formation of a cigarette mouthpiece in which the inner end of the blank lies across the bore of the mouth-piece and forms a positive tobacco stop. By referring to Figs. 8 and 9, it will be seen that the end of the blank protrudes somewhat beyond the spindle and that when the blank is coiled up, this protruding end is bent over against the spindle, a cigarette mouthpiece being produced which has a web lying directly across its bore, this web being stiff enough to prevent the insertion of the tobacco filler too far into the mouth-piece.

A cigarette such as referred to forms the subject-matter of Letters Patent No. 843,628, dated Feb. 12, 1907, granted to The American Tobacco Company as assignee of S. I. Prescott.

After the mouthpiece blank is formed up, it is introduced into the cigarette tube by suitable mechanism. In the construction illustrated, there is employed a slotted introducing tube 66, this tube being supported in a clamp block 67 carried on an arm 68, this arm being mounted on a slide 69. This slide is supported on the tie rod 62 before referred to and a companion rod 70 and is operated from any suitable source of power by means of a link 71 and a lever 72. In the particular machine illustrated, the forward end of the blank, after passing through a suitable guide 73 (see Fig. 6) enters the slit in the mouth-piece spindle and is wound up, the introducing tube being moved back over the coiled mouthpiece at just about the time the winding is completed. The introducing tube then moves forward, carrying the mouthpiece. The friction between the mouthpiece and the inner surface of the tube may be relied upon to strip the mouthpiece from the winding spindle or a positive stripping device may be employed. In

the construction illustrated, the arm 68 carries a small stripping spring 74 which is constructed to ride over the mouthpiece on the spindle as the introducing tube moves back, the spring, after the backward movement of the introducing tube is completed, snapping in behind the wound blank on the spindle. The introducing tube now moves forward and inserts the mouthpiece into a cigarette tube which may be supported in any suitable manner. The position of the end of the tube is indicated at 75 in Figs. 6 and 7. After the introducing tube has inserted the mouthpiece into the paper tube, it retreats, carrying the paper tube and inserted mouthpiece, the completed cigarette shell being stripped from the introducing tube by a pivoted spring operated stripper finger 76 of well-known construction.

It is customary in machines for forming cigarette shells containing mouthpieces to subject the completed shells to what is known as a rerolling operation, the purpose of which is to slightly expand the coiled mouthpiece to insure that it fits tightly in the paper tube. The bed may be provided with an inclined extension 81 upon which the cigarette shells which are stripped from the introducing tube in the manner hereinbefore described drop. A curved arm 83 is employed for forwarding the shells from the table 81 into the channel between the roll 77 and the bed 78, this arm being secured by a pair of clamps 84 to a rock-shaft 85. To operate this arm, the shaft 86 of the rerolling roll is provided with a cam disk 87 and the shaft 85 carries an arm 88 which is forced against the circumference of this cam disk 87 by means of a spring 89. At the proper time, the arm 88 will be forced by its spring 89 into the depression 90 of the cam disk and the introducing arm will be thrown forward to positively force the shell into the rerolling channel. The rerolling mechanism which includes a rerolling roll 77 coöperating with the bed 78 is operated from a gear 91 on a shaft 86 (see Figs. 1 and 6) which meshes with an idler 92, this idler being driven from a gear 93 on a main operating shaft 94, this shaft being driven from any suitable source of power.

The completed shells may be discharged into any suitable receptacle, as, for instance, a magazine, indicated at 95, and, if desired,

stripper fingers, indicated at 96, may be employed to insure such delivery.

The shaft 44, which is the shaft which carries the crank pin 41 and the disk 54, may be driven by a suitable gear, not shown, from the idler 92 and the gear 93 may (see Fig. 1) through an idler 97 and a gear 98 drive the cam 27 which is the cam which operates the rod 25.

Changes and variations may be made in the construction by which the invention is carried into effect. The invention is not, therefore, to be limited to the specific construction herein shown and described.

What is claimed is:

1. In a machine for making cigarette mouthpieces and in combination means for forwarding a strip of mouthpiece material, means for giving the strip a neck forming cut extending inward from one edge of the strip, and a blank severing cut, said cuts intersecting, and blank coiling and mouthpiece inserting means, said means receiving the narrowed neck of the mouthpiece blank formed by the cutting means.

2. In a machine for making cigarette mouthpieces and in combination means for forwarding a strip of mouthpiece material, means for giving the sides of the strip neck forming cuts extending inward toward each other from the edges of the strip and a blank severing cut which intersects the neck forming cuts, and blank coiling and inserting means which receive the narrowed necks of the mouthpiece blanks formed by the cutting means.

3. The combination with means for forwarding a strip of mouthpiece material, of forming knives for producing neck forming cuts in the opposite sides of the strip extending from the edges inward, a severing knife arranged to produce a cut intersecting the forming cuts, a blank coiling mechanism which receives the narrowed neck formed by the cuts, a tube support, and a re-rolling mechanism to which the tube and inserted mouthpiece are delivered.

In testimony whereof, I have hereunto set my hand, in the presence of two subscribing witnesses.

SYDNEY I. PRESCOTT.

Witnesses:

A. WHITE,
G. GALIANI.
